UNITED STATES PATENT OFFICE

1,981,661

BUILDING CONSTRUCTION

Frederick W. Pfeifer, West Allis, Wis.

Application May 24, 1933, Serial No. 672,627

29 Claims. (Cl. 72—1)

This invention relates to building construction and more particularly to a building construction erected from pre-formed or pre-cast members.

Various attempts have been made to apply pre-cast cement blocks to the construction of buildings. These blocks, while being partially successful in the construction of walls have utterly failed to adapt themselves to floor and roof construction. This is partly due to the low tensile strength of the material and partly to the weight and thickness of material required to span the floors.

It was sought to remedy this condition by the use of steel in place of the cement blocks. The advantages in cost of construction gained by the use of pre-formed steel sections was, however, more than offset by the increase in the cost of properly insulating the house against changes in temperature. The failure of the steel unit was further precluded by its size, which, to be economical, must be relatively large and therefore admitted of but a single box-like type of structure, and precluded flexibility of design.

It is an object of the present invention to provide a relatively small light weight pre-cast section or block that will adapt itself to floor and roof as well as to wall construction.

It is another object of this invention to combine the small pre-cast Portland cement sections with a system of steel webs or steel joists to form a relatively large structure, the joists or webs carrying the tensile stress, while the cement block carries the compressive stress.

It is a further object of this invention to provide a system of building which will permit a wide range of flexibility of design in which all units are pre-formed and assembled by bolts.

Another object is to produce a standard pre-formed cement section for use in the construction of buildings to which lathing and sheathing may be nailed at will.

A further object is to provide a tile for use in building construction that can be readily and economically manufactured.

Another object is to provide a tile of light weight concrete having great strength and rigidity.

These and other objects the nature of which will become apparent upon consideration of the following specification are accomplished by means of the structure shown on the accompanying drawings and described in the following specification, the invention residing in the par-

ticular combination of elements recited in the appended claims.

In the drawings:

Fig. 1 is a perspective view of a portion of the interior of a building constructed according to the precepts of this invention. 60

Fig. 2 is a cross-section of the building showing details of the floor, wall and ceiling connections. 65

Fig. 3 is a cross-section taken on the line 3—3 of Fig. 2. 70

Fig. 4 is a horizontal section taken on the line 4—4 of Fig. 2 showing the floor and wall construction, parts being broken away to more clearly show certain other parts. 75

Fig. 5 is a cross-section on the line 5—5 of Fig. 4 looking in the direction of the arrows. 80

Fig. 6 is a cross-section of a portion of the side of the building showing the connection of the flooring system to the side wall. 85

Fig. 7 is a cross-section on the line 7—7 of Fig. 6, looking in the direction of the arrows. 90

Fig. 8 is a cross-section through a window casting showing details of the supporting angle. 95

Fig. 9 is a detail of a load bearing partition showing details of the tie-in between the partition, the flooring and the supporting girder. 100

Fig. 10 is a cross-section on the line 10—10 of Fig. 9 looking in the direction of the arrows. 105

Referring to the drawings in which like numerals indicate like parts throughout the several views, the building is shown composed of a foundation 11, which supports side walls generally designated 12, end walls 13, first floor 15, a second floor or attic 16, and a roof generally designated 18, with one or more load bearing partitions 20 as shown in Figs. 9 and 10 intermediate the side or end walls. 110

While the building is shown as having only two floors it will be understood that the invention is not to be limited to such a height but may have any number of floors desired. 115

The walls, floors, roof and load bearing partitions are built up from a plurality of tiles or blocks 25, the blocks being identical in shape and size throughout the building except as noted below. Referring to Fig. 4 which shows the construction of the blocks most clearly, it will be seen that the blocks are substantially channel shaped in cross-section, with legs 26 extending out from the main slab 27. Fillets 29 are formed in the corners between the legs 26 and the slab 27 to strengthen the legs and prevent breakage thereof. The block 25 is preferably made of a light weight Portland cement material consist- 120

- ing of blast furnace slag, cement and water, which is known commercially as "Potsco", and fully described in U. S. Patent No. 1,816,988, is issued to Harry H. Potts on August 4, 1931.
- 5 A second material that may be used for the tile is known as "Haydite" and comprises a mixture of specially heat treated clay or shale, mixed with a proper quantity of cement and water.
- 10 Both of the above materials give a strong concrete like material which may be cut with a wood saw and into which nails may be driven at will for the fastening of laths while at the same time they are considerably lighter than regular concrete.
- 15 The tile sections 25 are reinforced with a wire mesh 32, the outer ends of the mesh being bent downward into the legs of the channel to transmit stress into the legs and prevent breakage thereof.
- 20 The legs of the channel are protected by metal binders 34 which are attached to the outer faces of the legs by means of punched out tabs 35 and bent up lower ends 36, which project into the cement mixture. The binders 34 run throughout the length of the legs and serve to protect them 25 against chipping and breakage. Holes 41 are formed in the legs of the tiles 25, the holes extending through the binders 34 to accommodate assembling bolts, to be described below.
- 25 A channel shaped bend 38 is formed in the binders 34 which projects into the concrete of the block parallel to and adjacent the outer face of the slab 27 to form a channel-shaped groove or recess therein, to retain a weather stripping 40. The weather stripping is inserted in the 30 grooves 38 in adjacent tiles and may run throughout the length of the floor or the height of the walls or roof to prevent the entrance of weather into the structure and retard the passage of heat from the structure.
- 35 The ends of the tile sections are provided with V shaped grooves 42 lying approximately in the same plane as the grooves 38. Square rods 43 fit into the V grooves in adjacent tiles and extend substantially the entire distance between 40 adjacent weather strippings 40 to form a protection against the weather entering the building between the end surfaces of the tiles.
- 45 Referring to Fig. 1, it will be seen that the floor 15 is built up on a series of steel joists 45, which support the tiles 25. The joists 45, which are best shown in Figs. 2 and 3, are preferably of the built-up type having a web 46 and a pair of angles 47-47 fixed thereto at the lower edge thereof in the usual manner. The angles 47 are bent up vertically at the wall line as shown at 47', the bent up portion forming a stiffener which prevents crushing of the web, and adds to the general rigidity of the structure.
- 50 The web 46 is punched at intervals as shown at 48, the punchings being bent out alternately on opposite sides of the web to form shelves 49 upon which the tiles 25 rest during the assembling operation. Holes are punched in the web 46 to correspond in spacing with the holes 41 formed in the legs of the tiles 25, the aligned holes receiving assembling bolts 50.
- 55 The bolts 50 may be provided with shoulders on the end remote from the head, about which fit a wedge fork member 51, the bolt being drawn tight by the wedge, and the prongs of the fork being pinched together to hold the wedge in place. While this has been found to be the most convenient type of fastening other types may be used if desired.
- 60 The recesses formed by the bend 38 lie parallel to and adjacent the metal web 46 so that the recesses in the sections on the opposite sides of each web face each other. Weather stripings 40, heretofore described, extend across the web 46 between the grooves in the sections on the opposite sides of the web 46 and run throughout the length of the floor. Similarly V-shaped notches 41 mate with each other in the transverse joints, and square weather stripings 43 are inserted in the mating notches 41 and extend substantially between the grooves 38 in each block. It will be noted that whereas the longitudinal weather stripping extends between grooves on the opposite sides of a web 46, the weather stripings 43 extend into notches or grooves in sections lying on the same side of the web.
- 65 The entire floor is supported by the end walls 13, which in turn rest directly on the foundation 11.
- 70 Any number of floors may be used in the house, the construction of all floors being identical with that of the first floor described above as are their connections with the side and end walls, 100 described below.
- 75 The end wall 13 and the side wall 12 are built up from a plurality of tiles 25 placed vertically on end with the inner portion of the channel facing the interior of the structure as shown in Fig. 1. As shown in Figs. 2 and 4 there are web plates 54 between the tiles 25 which are of somewhat less width than the width of the legs 26, so as not to project past the outer edge of the leg, the web plates serving to hold the wall assembled and to absorb a major portion of the tensile stress from wind and other bending forces. Holes are punched in the web plates 54 which correspond in spacing with the holes 41, in the tiles 25, the aligned holes accommodating 110 assembling bolts 50 and wedge locks 51 heretofore described.
- 80 The end wall 13 and the side wall 12 are built up from a plurality of tiles 25 placed vertically on end with the inner portion of the channel facing the interior of the structure as shown in Fig. 1. As shown in Figs. 2 and 4 there are web plates 54 between the tiles 25 which are of somewhat less width than the width of the legs 26, so as not to project past the outer edge of the leg, the web plates serving to hold the wall assembled and to absorb a major portion of the tensile stress from wind and other bending forces. Holes are punched in the web plates 54 which correspond in spacing with the holes 41, in the tiles 25, the aligned holes accommodating 115 assembling bolts 50 and wedge locks 51 heretofore described.
- 85 The joist 45 has the web 46 thereof, extended at the walls past the end of the floor tile 25 adjacent the wall 13 as shown at 57, the end 120 57 projecting between adjacent tiers of tiles 25 in the end wall, where it is fastened by a pair of bolts 58 to the wall tiles 25, the bolts 58 being similar to the bolts 50 heretofore described.
- 90 It will be noted in Fig. 2 that it is desirable 125 to support the joists 45 by two bolts 58. In order to accomplish this without the necessity of making a special hole in the pre-cast sections 25, as well as to secure uniform spacing between the floors of a multi-storied building, the tiles 130 25 end approximately in the center of each joist 45, and one bolt 58 passes through each of the two tiles adjacent the joist 45. At the ground floor and at the roof it is necessary to supply a short tile 60 and 62 respectively to form the 135 support for one of the bolts 58. The short sections 60 and 62 are similar in cross-section to the tiles 25, and have a hole formed in each leg to secure it to the adjacent floor section.
- 95 Since the ends 57 of the webs 46 project into 140 the wall, between the tiers of wall tiles or sections 25, the webs 54 in the end wall 13 extend from the top of the lower joist to the bottom of the next joist above it. It will be noted, that, since each tile 25 contains three bolt holes, 145 the tiles next to the joists are held by two bolts through the web 54 and one through the end 57 of the web 46.
- 100 The webs 54 in the side walls may run the entire height of the wall, as there are no floor 150

joists projecting between the tiers in that wall.

The side walls 12 are similar to the end walls except that the webs 54 run straight through without breaks at the floors.

5 The connection of the side walls to the floor is best shown in Figs. 6 and 7. The end joist 63 of the floor is made with but a single angle, since it is desirable to have it fit flush against the side wall 12. This is possible since it has 10 approximately half the load to carry. The web of the joist 63 thus fits flush against the side of the wall 12 and is held against that wall by eye bolts 65 which are attached to the wall by the assembling bolts 50 and which pass 15 through holes drilled in the web of the end joist 63.

Referring to Figs. 1 and 4 it will be seen that the entire wall structure is stiffened by the addition of a square pre-cast section 67, made 20 of the same material as the tiles 25. The corner sections 67 are bound on two adjacent sides with a metal binder 70, having channel bends 71 therein which project into the sections 67 to form a channel-shaped groove or recess similar 25 to the recess 38 in the tiles 25 corresponding to the channels 38 in the tiles and which accommodate weather stripplings 40 between the tiles and the corner sections. A plurality of 30 bolts 73 are imbedded in the section 67 at spacings conforming with the holes in the legs of the tiles 25. It is preferable to use a single bolt for this purpose as shown in Fig. 4, the bolt being bent at right angles within the casting and having fastening means on both outer ends thereof. Web plates 54, similar to those heretofore described are used between the legs of the 35 tiles 25 and the corner sections 67 to form a rigid structure.

While the corner section 67 is shown as square 40 in cross-section, it may also be made in the shape of any angled rhombus to give a corresponding angle to the corner.

The roof 18 is formed by a plurality of spaced 45 parallel joists 78 having a web plate 79 and a pair of angles 80—80 back to back at the lower edge thereof. If the roof is peaked, as shown in Figs. 1 and 2, the angles are bent so that the ends of the angles are parallel to the floors as shown at 81, while the upper end of the angle 50 is bent perpendicularly to the floor as shown at 82 and mates with upturned ends 82 of the angles 80—80 on the other half of the roof. The two halves of the roof 18 are fastened together by bolts 86 passing through the two up-standing ends 82 of the angles 80. If desired 55 a web plate 84 may be used between the up-turned ends 82 of the angles 80 of the two halves of the roof to generally stiffen the structure.

The horizontal portions 81 of the angles 80 60 rest on angles 90 which are held on the tops of the walls 13 by the weather stripplings 40 which project through holes in the horizontal leg of the angle 90 and are clinched down on it, the friction of the weather stripplings 40 in the 65 recesses 38 insuring the angles 90 being held in place. If desired the frictional force on the weather strippling may be further augmented by bending the lower end of the strip 40 and securing it between the lower edge of the wall 12 70 and the foundation, as shown at 91.

The outer edge of the horizontal portion 81 of the angle 80 abuts the vertical leg of the angle 90, the vertical leg of the angle 90 preventing the lateral movement of the roof on the structure. 75

As best shown in Figs. 1 and 2, the roof 18 is held down on the building by means of tabs 92 which are punched from the angle 90 and clinched down over the horizontal leg of the angles 81.

80

Windows and doors are inserted by leaving out an appropriate number of tiles 25 and supporting the tiles above the door or window by means of an angle 95, shown in Figs. 1 and 8. The angle 95 is provided with an angle bracket 96 at each end thereof which is fastened by means of a bolt 50 and nut 51 to the upper tiles at the sides of window or door. It is obvious that for narrow doors or windows, not more than two or three tiles in width, no angle 95 will be needed, since the load will be transmitted through the bolts 50, in the tiles above the window, to the sides of the opening.

85

90 Figs. 9 and 10 show a load bearing partition to be used intermediate the sides of the structure. The partition rests on an I beam 100 which may run unsupported throughout the length of the building or which may have one or more supports intermediate the ends, in the manner well known in the building industry. 100 The joists 45 are fastened to the I beam 100 by angle brackets 102 while connector plates 103 join the webs 46 of the joists 45 at the upper edge, above the top of the I beam. The partition which runs from the top of one floor to 105 the bottom of the joist of the next floor above, is built from a plurality of tiers of tiles 25 in the same manner as the walls 12 and 13.

95

The interior of the house may be finished by 110 nailing lath to the tiles, and plastering, as shown at 97, while flooring 98 and window frames 99 and door jambs (not shown) may be inserted in the usual manner.

The exterior of the house may be finished in 115 brick, stucco or other material in the usual manner.

Having thus described the invention it will be realized that it is susceptible to various changes and modifications, and it is not, therefore, desired to limit the scope of the invention 120 to the particular form herein shown and described, but only by the scope of the appended claims.

What is claimed as new and desired to secure 125 by Letters Patent is:

1. In a building construction, a load bearing member comprising, a plurality of pre-formed sections, a joist comprising a web, and a tension member on the lower edge thereof, and means to attach said sections to the upper portion of 130 said web.

2. In a building construction, a load bearing member comprising, a plurality of pre-formed sections, a joist comprising a web, and a tension member on said web on the lower edge thereof, 135 means on said web to support said sections in position on said web above said tension member during construction, and means to attach said sections to the upper portion of said web.

3. In a building construction, a floor comprising 140 a joist including a web and an angle fastened on the lower edge thereof, and a plurality of pre-cast cement sections fastened to said web on the upper part thereof, a wall comprising a web, a plurality of pre-cast cement sections and 145 means to hold said last named sections integral with said last named web, and means securing said first named web to the pre-cast sections of the wall, whereby said floor is supported from said wall.

4. A pre-cast cement tile for use in building construction comprising, a flat slab having a plurality of sides, a metal binder on the two longitudinal edges thereof, said binder having 5 a channel-shaped bend therein projecting into said tile to accommodate a weather stripping, the other sides of said tile having recesses there- in extending substantially from one said chan- nel-shaped recess to the other to accommodate 10 other weather stripplings.
5. In a building construction of the character described, a load bearing member comprising, a plurality of rows of pre-formed sections, a metal web between each of said rows, a weather strip 15 extending between longitudinal grooves in ad- jacent rows of sections parallel to said webs, and weather stripplings extending into grooves in the transverse edges of said sections substantially the width of each section.
- 20 6. In a building construction, a load bearing surface comprising, a plurality of pre-formed substantially channel shaped concrete sections, a joist comprising a web and a tension member attached to said web on one edge thereof, and 25 bolts passing through alined holes in the legs of said channel shaped sections and the web, to attach the sections to the web on the edge there- of remote from the tension member.
7. In a building construction, a load bearing 30 member comprising, a joist having a web and a tension member attached to the lower edge thereof, a plurality of pre-formed substantially channel shaped sections having metallic binders on the longitudinal edge thereof arranged on both sides of said web, and bolts passing through 35 alined holes in the legs of said channel shaped sections and said web to attach said sections to the upper edge of the web.
8. A building construction as defined in claim 40 7 including a weather stripping extending be- 7 between grooves in adjacent sections on the op- posite sides of said web.
9. A building construction as defined in claim 45 7 including a weather stripping extending be- 7 between grooves in adjacent sections on the op- posite sides of said web and weather stripplings 45 extending between grooves in adjacent sections on the same side of the web.
10. A building having a floor comprising, a 50 joist including a metal web and a tension member fixed to the lower edge thereof, and a plu- rality of pre-formed cement sections secured to said web and to each other adjacent the upper edge of the web, a vertical wall comprising a web, and a plurality of pre-formed sections secured 55 to said web and to each other, said first named web extending between the sections of said wall and bolts passing through alined holes in the wall sections and floor web to support the floor 60 from the wall.
11. A building construction as defined in claim 10 including a stiffener for said joist web fixed thereto adjacent said wall.
12. In a building construction of the charac- 65 ter described, a wall comprising a plurality of rows of pre-formed cement sections with weather stripplings projecting into recesses in said sec- tions and extending vertically between the rows, an angle iron on top of said wall, held thereon by said weather stripping, a roof comprising a 70 plurality of rows of pre-formed sections, a metal web between each of said rows and a tension member on the lower edge of said web, said ten- sion member resting on said angle and retained 75 thereon by the vertical leg thereof.
13. A building construction as defined in claim 12 including means on the horizontal leg of said angle engaging said tension member to prevent movement of said roof. 80
14. In a building construction, a load bearing member comprising, a plurality of pre-formed substantially channel shaped sections, a metal plate running lengthwise between said sections, and bolts passing through alined holes in the legs of said sections and said plate to hold the sec- tions assembled with each other and with said plate. 85
15. In a building construction a load bearing member comprising, a metal web, a pluarlity of pre-cast substantially channel-shaped concrete sections arranged on both sides of said web, and bolts passing through aligned holes in the legs of said channel-shaped sections and through said web to hold the sections assembled with each other and with said web. 90
16. In a building construction of the character described, a flat load bearing member comprising, a plurality of rows of pre-formed sections, a metal web between each of said rows, and separate means extending into said sections and across the joints therebetween to prevent the passage of weather through said surface. 95
17. A building construction including a wall, a floor comprising, a metal tension member and a plurality of preformed cement sections at- 100 tached to said tension member, said tension member extending beyond the end of the cement sections and into said wall, and means securing said tension member to said wall, whereby the floor is supported from the wall. 105
18. In a building construction of the charac- 110 ter described, an end wall comprising, a pluarlity of preformed sections and means to bind said sections together to form a rigid wall, a side wall at an angle to and abutting said end wall, said side and end walls being connected together, a floor comprising a metal tension member with a plurality of preformed cement sections attached thereto, said tension member extending beyond the end cement section and into said end wall between the sections thereof, means securing said extension to the preformed sections of the end wall whereby said floor is supported therefrom, and means on said side wall binding the side wall to said floor to form 120 a rigid structure. 125
19. In a building construction including a roof and a plurality of walls with weather stripping between the joints of said walls, a roof retaining member on the top of one of said walls having a horizontal and a vertical leg, said weather stripping extending above said last named wall and through one of said legs and clamped thereon to retain said member in position on said wall. 130
20. In a building construction including a roof and a plurality of walls with weather stripplings between the joints of said walls, a roof retaining member on the top of one of said walls in- 135 cluding a horizontal and a vertical leg, the weather stripping of said last named wall ex- tending thereabove and through one of said legs and clamped thereon to retain said member in position on said wall, and means on one of said legs to retain said roof in position on said walls. 140
21. In a building construction, a load bearing member comprising, a metal web, a plurality of preformed substantially channel-shaped sections arranged on both sides of said web, each of said 145 150

sections having a groove in the side adjacent the web, bolts passing through aligned holes in the legs of said channel-shaped sections and said web to hold the sections assembled with each other and with said web, and a weather stripping extending across said web between the grooves of adjacent sections.	projecting into said member to form a recess therein adapted to accommodate a weather stripping.
22. A building construction as defined in claim 21 including weather stripping extending between grooves in the transverse joints of adjacent sections on the same side of said web.	26. In a building construction of the character described, a flat load bearing member comprising, a plurality of rows of pre-formed channel-shaped sections having metal binders on the longitudinal edges thereof with channel-shaped bends therein projecting into said sections to form recesses in the longitudinal edges thereof, a metal reinforcing web between each of said rows and a weather stripping extending into the recesses in adjacent sections on the opposite sides of said web.
23. A preformed section for use in building construction comprising a substantially channel-shaped concrete member having a flat surface and a pair of legs substantially at right angles thereto, and a metallic binder on the outer edge of each of said legs, each of said binders having a channel-shaped bend projecting into said member to accommodate a weather stripping.	27. A building structure as defined in claim 26 including weather stripings extending between and into recesses in the transverse joints between adjacent sections on the same side of the web.
24. A preformed section for use in building construction comprising, a substantially channel-shaped member including a flat surface, a pair of legs substantially at right angles thereto and a metallic binder on the outer edge of each of said legs, each of said binders having a channel-shaped bend therein projecting into said member to accommodate a weather stripping, said legs and said binders having aligned apertures therein to receive assembling bolts.	28. In a building construction, a load bearing member comprising, a plurality of pre-formed sections having grooves in the longitudinal edges thereof, a joist comprising a web, and a tension member on the lower edge thereof, means to attach the sections to the web with the longitudinal edges adjacent the web, and a weather stripping extending across the web and into the grooves in the sides of the section adjacent the web.
25. A tile for use in building construction comprising, a pre-formed channel-shaped member including a pair of spaced legs joined by a flat slab portion, a metal binder on the outer face of each leg, each of said binders having a bend	29. A building construction as defined in claim 28 including weather stripings extending into grooves in the transverse edges of adjacent sections.
